UNITED STATES PATENT OFFICE.

CHARLES WALTER WATKINS, OF DORRANCETON, PENNSYLVANIA.

RAILWAY-BRAKE.

1,322,852.

Specification of Letters Patent. Patented Nov. 25, 1919.

Application filed June 25, 1919. Serial No 306,634.

To all whom it may concern:

Be it known that I, CHARLES W. WATKINS, citizen of the United States, residing at Dorranceton, in the county of Luzerne 5 and State of Pennsylvania, have invented certain new and useful Improvements in Railway-Brakes, of which the following is a specification, reference being had to the accompanying drawings.

- 10 This invention relates to certain improvements in brakes for railroad cars and has relation more particularly to a brake specially adapted for use in connection with a mine car, pleasure car or the like traveling by gravity; and it is an object of the invention to provide power operated means for frictionally engaging the axle or axles of a car to retard its movement so that the use is dispensed with of sprags or snubs and 15 whereby speed of the car may be retarded or the car brought to a stop without a sudden shock or bump which would otherwise impose excessive wear and tear upon the car.
- 20 It is also an object of the invention to provide a novel improved brake of this general character including a skid supported for vertical swinging movement and operated by fluid pressure to have frictional engagement with a car to retard the movement thereof.
- 25 Another object of the invention is to provide a novel improved device of this general character including a vertically movable skid together with a fluid operated piston operatively engaged with the skid for imposing movement to the skid in a direction to frictionally engage a car, together with means whereby the movement of the 30 piston is cushioned in order to prolong the life of the device and to minimize the possibility of injury thereto.

The invention consists in the details of construction and in the combination and arrangement of the several parts of my improved brake whereby certain important advantages are attained and the device rendered simpler, less expensive and otherwise more convenient and advantageous for use, 45 as will be hereinafter more fully set forth.

The novel features of my invention will hereinafter be definitely claimed.

In order that my invention may be better

understood, I will now proceed to describe the same with reference to the accompanying drawings, wherein:

Figure 1 is a view partly in longitudinal section and partly in elevation illustrating a railway brake constructed in accordance with an embodiment of my invention a car 60 being diagrammatically indicated.

Fig. 2 is a view in top plan of the structure illustrated in Fig. 1 with the car and the regulating valve omitted.

Fig. 3 is an enlarged sectional view taken substantially on the line 3—3 of Fig. 1.

Fig. 4 is an enlarged fragmentary view partly in section and partly in elevation illustrating means as herein disclosed for elevating the skid.

Fig. 5 is a fragmentary view in top plan illustrating adjacent ties and the butts or timbers interposed therebetween.

Fig. 6 is a fragmentary view partly in section and partly in elevation illustrating the regulating valve as herein employed.

As disclosed in the accompanying drawings, T denotes the cross ties of a track structure upon which are rested the rails R over which a mine car, a pleasure car or other 80 unit of rolling stock is adapted to travel. Mounted upon adjacent ties T substantially midway between the rails R is an upstanding block B having its opposite ends beveled as at 1 so that the couplings carried by the 85 rolling stock may drag thereover without catching.

The block B serves as a journal for the shaft 2 disposed transversely therethrough and extending beyond opposite sides thereof. Secured to each extended portion of the shaft 2 is an elongated skid S. The skid S is preferably formed of wood and has disposed along its upper or working edge or face a rail plate 3 of metal. The skid S is 90 also arranged substantially in parallelism with the rails R and extends in the same general direction as the direction of travel of the car or rolling stock so that when the end portion of the skid remote from the 100 block B is raised or elevated, the skid S will have frictional contact with the axle A of the car C whereby the speed of the car is retarded without the necessity of spragging, snubbing or blocking as is now generally 105 done and particularly in mines.

Depending from the free or working end portion of the skid S is a pair of transversely spaced ears 4 between which is pivotally engaged the base portion of a coupling member 5 substantially in the form of an inverted U. The coupling member 5 straddles the upper or outer end portion of the piston rod 6 with its side members a pivotally engaged with the piston rod 6. The piston rod 6 is mounted for rectilinear movement and the coupling member 5 compensates for the requisite swinging movement of the skid S without throwing the rod 6 out of plumb and which is readily permitted because the stroke of the rod 6 is short.

The inner or lower end of the rod 6 is engaged with a piston 7 reciprocating within a cylinder 8. The upper head 8a of the cylinder 8 is provided with a stuffing box 9 through which the rod 6 travels so that leakage is avoided.

The head 8a is also preferably rectangular in plan so that the corners 8b thereof afford outwardly and laterally extending flanges whereby the cylinder may be engaged with and supported between adjacent ties T and the butt or timbers 10 interposed between said adjacent ties.

In practice the piston 7 has a stroke of about four inches and the upward stroke of the piston 7 is under control of an air cushion formed between said piston 7 and the upper head 8a whereby the piston 7 is prevented from striking said head 8a with force and particularly upon sudden release of the weight of the rolling stock upon the raised skid S.

In the present embodiment of my invention the air cushion is formed through the instrumentality of the check valve 11 opening on the downward stroke of the piston 7 and closing in the upward stroke. In other words, as the piston 7 moves downwardly the check valve 11 opens to admit air within the cylinder 8 and when the piston 7 is moved upwardly air within the cylinder 8 above the piston is compressed to afford the desired cushion. In communication with the lower portion of the cylinder 8 and below the piston 7 is a pipe line 12 leading from a suitable source of fluid under pressure and which fluid may be air, water or steam. Interposed within the pipe line 12 is a three-way valve 14 wherein the plug is operated through the medium of the upstanding lever 15. When it is desired to raise the skid S the lever 15 is thrown into a position to permit the unobstructed flow of the fluid under pressure within the cylinder 8 and upon adjusting the lever 15 into a second position the pressure within the cylinder 8 will be released and the skid S will lower by gravity to a position clearing the axles A and preferably at a position

substantially one-half inch below such axles.

In order to prevent the piston 7 from striking the lower head of the cylinder 8 I find it of advantage to provide upon the upper surface of one of the ties T and below the skid S a bumper or buffer 16 formed of yielding material and preferably rubber. This buffer or bumper 16 serves to cushion the weight of the skid S and the parts concomitant thereto.

The speed of the upward stroke of the piston 7 will be in proportion to the pressure of the fluid and to the area of the fluid inlet of the cylinder 8. In some cases the downward stroke of the piston 7 under the influence of the weight of the car upon the skid S will raise the pressure within the cylinder above the inlet pressure and in this case the extra pressure will flow or be forced back in the line 12. In the event the compression on the upward stroke of the piston 7 becomes too high for proper action I provide the air cup 17 which may be set to reduce such excessive compression.

The working end portions of the skids S are connected by a cross member 18 having secured to its upper surface a buffer or cushion 19 formed of yielding material, preferably rubber, and this cushion or buffer 19 is adapted to engage upon upward movement of the skids S, the rigid member 20 extending over said cross member 18 and supported by adjacent ties T. In practice the buffer or cushion 19 commences to compress between one-quarter and one-half inch before the piston 7 reaches the limit of its upward movement and whereby a further aid is given to the desired compression. The member 20 is of a length substantially equal to the distance between the skids S so that said member also serves as a guide whereby the skids S are held against undue lateral movement and thereby maintained in desired alinement. It will also be understood that the area of the inlet for the fluid within the cylinder 8 can be increased or decreased to give more compression and greater pressure, together with quicker action or vice versa and it is also to be understood that when the pressure may be too high a reducing valve (not shown) of any desired type may be employed.

From the foregoing description, it is thought to be obvious that a brake constructed in accordance with my invention is particularly well adapted for use by reason of the convenience and facility with which it may be assembled and operated and it will also be obvious that my invention is susceptible of some change and modification without departing from the principles and spirit thereof and for this reason I do not wish to be understood as limiting

myself to the precise arrangement and formation of the several parts herein shown in carrying out my invention in practice except as hereinafter claimed.

5 I claim:

1. A device of the character described comprising a skid supported for vertical swinging movement, a cylinder, a piston movable within the cylinder and operatively engaged with the skid, and means for admitting fluid pressure to the cylinder for moving the piston in a direction to elevate the skid, said cylinder being provided with means for producing an air cushion within the cylinder in advance of the piston when said piston moves in a direction to elevate the skid.
- 10 2. In combination with the rails of a trackway, a block positioned therebetween and having its opposite ends beveled, a shaft journaled in said block, a skid extending longitudinally of the trackway and having an end portion fixed to the shaft, and fluid operated means for imparting upward swinging movement to the skid.
- 15 3. A device of the character described comprising a skid supported for vertical

swinging movement and adapted to frictionally engage a car when elevated, fluid operated means for elevating the skid, and means coacting with the skid for limiting its upward movement and for holding the skid against lateral movement.

4. In combination with the rails of a trackway, a block positioned therebetween and having its opposite ends beveled, a shaft journaled in said block, a skid extending longitudinally of the trackway and having an end portion fixed to the shaft, and means for imparting upward swinging movement to the skid.

5. In combination with the rails of a trackway, a block positioned therebetween, a shaft journaled in said block, a skid extending longitudinally of the trackway and having an end portion fixed to the shaft, and means for imparting upward swinging movement to the skid.

In testimony whereof I hereunto affix my signature in the presence of two witnesses.

CHARLES WALTER WATKINS.

Witnesses:

MURRAY WERTHEISER,
WILLIAM J. SMITH.
